CAR DOOR CONSTRUCTION

Frank Ditchfield, Cleveland, Ohio, assignor to The Youngstown Steel Door Company, Cleveland, Ohio, a corporation of Ohio

Application August 26, 1943, Serial No. 500,077

8 Claims.

(Cl. 20—26)

This invention relates to car door construction and more particularly to the construction of the upper forward corner of sliding car doors and associated structure carried by the cars.

It is an object of this invention to provide a construction for the upper forward corner of sliding car doors and for the car side structure associated therewith which shall effectively improve the weathertightness of the doors at this corner.

A further object is to provide a construction of the character stated which shall dispose of dust, cinders, etc. beyond the door opening formed in the cars.

A further object is to provide a simple, inexpensive construction for accomplishing the results stated above.

Other objects of the invention will become clear as the description thereof proceeds.

In the drawing forming part of this specification:

Fig. 1 is a fragmentary elevation of the upper forward corner of a sliding car door and the adjacent car side, a portion being broken away to more clearly show the invention.

Fig. 2 is a horizontal section taken on line 2—2 of Fig. 1.

Fig. 3 is a vertical section taken on line 3—3 of Fig. 2.

Fig. 4 is a front elevation of one of the members embodied in the instant invention.

Fig. 5 is a side elevation of the member shown in Fig. 4.

Referring to the drawing wherein a preferred embodiment of the invention is illustrated, the numeral 10 designates generally a portion of the side wall of a railway house car adjacent to the upper forward corner of a door opening 11 formed in said wall. The door opening is defined in part by means of a side plate 12 which customarily embodies an upstanding flange 13, a web 14 and a depending flange 15 and by means of a front door post 16 shown fragmentarily in Figs. 2 and 3 of the drawing. Metallic sheathing 17 is secured to the leg 18 of the door post 16, as more clearly shown in Fig. 2 of the drawing. Also secured to the leg 18 of the door post is a front stop member 19 of well known construction embodying an attaching flange 20, an outwardly extending flange 21, a forwardly extending flange 22, an outwardly extending flange 23 and rearwardly and outwardly inclined flange 24. The flanges 22, 23, and 24 define a pocket 25 adapted to receive the front margin of a sliding car door 26.

The car door may be of any desired construc-

tion but, as illustrated, embodies a metallic panel 27 formed with a forwardly and outwardly sloping flange 28 which terminates in a flange 29 disposed parallel to the main plane of the door.

5 A front vertical reinforcing member 30 is secured to the panel flange 29 and, additionally, to the panel by means of a backing plate 31 fastened thereto inwardly of the sloping flange 28 and to the reinforcing member substantially in the main 10 plane of the panel. The upper horizontal margin of the door is reinforced by means of a member 32 shown in the form of a Z-bar and arranged with its web 33 vertical, one flange 34 extending outwardly, and the remaining flange 35 directed inwardly. It is to be understood that an angle member, or any other desired form of reinforcement, may be utilized in place of the Z-bar.

The upper margin of the door is slidably retained upon the car side between a door header

20 36 and a retaining bar 37. The door header 36 is substantially in the form of a J-shaped member having an upstanding flange 38 secured to the inner face of the depending side plate flange 15, an outwardly extending flange 39 and an

25 upwardly and outwardly extending flange 40, thereby providing a trough 41. The retaining bar 37 is preferably Z-shaped in section and includes a vertical attaching flange 42 secured to the outer face of the depending side plate flange

15, an outwardly extending web 43 disposed above the header 36, and a depending flange 44 disposed outwardly of the flange 40 of the header. The upper margin of the door is received between the flanges 40 and 44, respectively, of the header and the retaining bar. It will be apparent from

Fig. 3 of the drawing that the inwardly extending flange 35 of the Z-shaped reinforcing member 32 extends inwardly above the header flange 40 so as to overlie the trough 41.

Previous to the instant invention it was customary to extend the front stop 19 continuously from the door track disposed below the door opening 11 to the underside of the retaining bar 37. By reason of this construction it was necessary to terminate the header at the flange 21 of the door stop and to cut away a portion of the inwardly extending flange 35 of the door reinforcing member in order to avoid contact between this flange and flange 21 of the door stop

40 so as to permit the door to be fully closed. In view of this construction, a sizeable opening existed at the upper front corner of the door through which dust, cinders, rain and the like entered the car.

The instant invention avoids the cutting away

of the inwardly extending flange of the door reinforcing member and substantially improves the weathertightness of the upper front corner of the door. In accordance with this invention the front stop 19 is terminated below the header 36, as more clearly shown in Fig. 3 of the drawing. The outwardly extending flange 39 of the header and the upwardly extending flange 40 thereof can, therefore, be extended continuously beyond the flange 21 of the front stop. As more clearly appears from Fig. 2 of the drawing, it is preferred to remove a portion of the flange 39 of the header, as indicated at 45 and 46, so that the flange 39 follows substantially the outer contour of the flanges 21 and 22 of the door stop 19. By means of this construction, a portion of the flange 39 and the upwardly extending flange 40 of the header 36 terminate substantially in line with the inner face of the flange 23 of the door stop, as more clearly appears from Fig. 2 of the drawing. By reason of the described construction, it will be apparent, as clearly shown in Fig. 2 of the drawing, that the inwardly extending flange 35 of the door reinforcing member 32 extends continuously and without coping to the forward edge of the door.

To complete the construction at the front upper corner of the door and obtain a weathertight structure, the instant invention provides an angular closure member 47. The member 47 is preferably angular in section, as more clearly shown in Fig. 2 of the drawing, and embodies a flange 48 disposed at a right angle to the side wall. The flange 48 extends from the wall of the car to the depending flange 44 of the retaining bar 37 and from the web 43 of the retaining bar for a substantial distance downwardly below the flange 44, as more clearly appears in Figs. 1 and 2 of the drawing. The closure member also embodies a flange 49 of substantially the same extent as the flange 48 and arranged to abut and extend along the inner face of the depending flange 44 of the retaining bar to the outer face of flange 23 of the door stop. Securement of the angular closure member 47 may be had by means of welding to the wall and to the flange 23. The flange 49 of the closure member carries a relatively short flange 50 which extends inwardly toward the wall from the top of the flange 23 of the front stop to a point substantially in line with the upper surface of the inwardly extending flange 35 of the door reinforcing member 32. The flange 50 thereby terminates below the web 43 of the retaining bar. The flange 50 is preferably so arranged as to span the space between the depending flange 44 of the retaining bar and the upstanding flange 40 of the header against which it abuts. It is preferred, moreover, that when the door is in closed position, the inwardly extending flange 35 and a portion of the web 33 of the door reinforcing member 32 also abut the flange 50 of the closure member.

It will be apparent from the foregoing description taken in connection with the drawing that the closure member in conjunction with the car wall, retaining bar, and front stop, closes the end of the trough 41 of the header and provides a downspout 51 open at its lower end, which communicates with the header trough. Accordingly, any dust, cinders, rain and the like, which may enter the header trough, can be disposed outwardly of the car through the downspout. Also any dust, cinders and the like, which may fall upon the inwardly extending flange 35, may sim-

ilarly be disposed of through the downspout beyond the door opening.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway house car having a side wall formed with a door opening, a header having a flange secured to said wall, an outwardly extending flange and an upstanding flange, said flanges forming a trough, the front end of said trough being open, a front door stop secured to and along said wall adjacent to said door opening, said door stop terminating at said front end of said header, a door retainer secured to and along said car wall above said header, said retainer having a depending flange spaced outwardly of said header and lying above said door stop, and vertical closure means extending downwardly from the underside of said retainer a substantial distance below said header and cooperating with said wall, front stop and retainer to provide a spout communicating with the open end of said header, said means embodying an inwardly extending flange overlapping the end of said upstanding flange of said header and closing the space between said retainer flange and said upstanding header flange.

2. In a railway house car having a side wall formed with a door opening, a header providing a trough secured to said wall, the front end of said trough being open, a front door stop secured to and along said wall adjacent to said door opening, said door stop terminating at said front end of said header, a door retainer secured to and along said car wall above said header, said retainer having a depending flange spaced outwardly of said header and lying above said door stop, and a vertically extending angular closure member having a flange secured to and extending from said wall to said retainer flange forwardly of said header and front stop and a flange extending partly along said retainer flange to said front stop, said flanges of said member extending a substantial distance below said retainer and cooperating with said wall, retainer and front stop to provide a spout having a closed upper end and an open lower end communicating with the open end of said header.

3. In a railway house car having a side wall formed with a door opening, a header having a flange secured to said wall, an outwardly extending flange and an upstanding flange, said flanges forming a trough, the front end of said trough being open, a front door stop secured to and along said wall adjacent to said door opening, said door stop terminating at said front end of said header, a door retainer secured to and along said car wall above said header and lying above said door stop, said retainer having a depending flange spaced outwardly of said header and a vertically extending angular closure member, having a flange secured to and extending from said wall to said retainer flange forwardly of said header and front stop and a flange extending partly along said retainer flange to said front stop, said flanges of said member extending a substantial distance below said retainer and cooperating with said wall, retainer and front stop to provide a spout having a closed upper end and an open lower end communicating with the open end of said header, said latter flange of said closure member having

a flange extending toward said wall and overlapping the end of said upstanding flange of said header.

4. In a railway house car having a side wall formed with a door opening, a header having a flange secured to said wall, an outwardly extending flange and an upstanding flange, said flanges forming a trough, the front end of said trough being open, a front door stop secured to and along said wall adjacent to said door opening, said door stop terminating at said front end of said header, a door retainer secured to and along said car wall above said header and lying above said door stop, said retainer having a depending flange spaced outwardly of said header and a vertically extending angular closure member having a flange secured to and extending from said wall to said retainer flange forwardly of said header and front stop and a flange extending partly along said retainer flange to said front stop, said flanges of said member extending a substantial distance below said retainer and cooperating with said wall, retainer and front stop to provide a spout having a closed upper end and an open lower end communicating with the open end of said header, said latter flange of said closure member having a flange extending toward said wall and overlapping the end of said upstanding flange of said header, a sliding door mounted on said car, said door having a portion disposed between said header and said retainer flange an inwardly directed flange overlapping said header trough and adapted to abut said last mentioned flange of said closure member, the upper edge of said last mentioned flange of said closure member lying substantially in the plane of the upper surface of said door flange.

5. In a railway house car having a side wall formed with a door opening, a header providing a trough secured to said wall, the front end of said trough being open, a front door stop secured to and along said wall adjacent to said door opening, said door stop terminating at said front end of said header, a door retainer secured to and along said car wall above said header, said retainer having a depending flange spaced outwardly of said header and lying above said door stop, and a vertical closure member extending from said door stop along said retainer flange and then inwardly from said retainer flange to said wall in spaced relation to said front end of said trough and upwardly to the underside of said retainer, said closure member having a flange extending upwardly from said door stop and inwardly, said closure flange lying forwardly of said front end of said header and terminating short of said wall.

6. In a railway house car having a side wall formed with a door opening, a header providing a trough secured to said wall, the front end of said trough being open, a front door stop secured to and along said wall adjacent to said door opening,

said door stop terminating at said front end of said header, a door retainer secured to and along said car wall above said header, said retainer having a depending flange spaced outwardly of said header and lying above said door stop, and a vertical closure member extending from said door stop along said retainer flange and then inwardly from said retainer flange to said wall in spaced relation to said front end of said trough and upwardly to the underside of said retainer, said closure member extending a substantial distance below said header, the portion of said closure member extending along said retainer flange carrying a flange extending upwardly from said door stop and inwardly, said closure flange lying forwardly of said front end of said header.

7. In a railway house car having a side wall formed with a door opening, a header providing a trough secured to said wall, the front end of said trough being open, a front door stop secured to and along said wall adjacent to said door opening, said door stop terminating at said front end of said header, a door retainer secured to and along said car wall above said header, said retainer having a depending flange spaced outwardly of said header and lying above said door stop, and a vertical closure member extending from said door stop along said retainer flange and then inwardly from said retainer flange to said wall in spaced relation to said front end of said trough and upwardly to the underside of said retainer, said closure member extending a substantial distance below said header, the portion of said closure member extending along said retainer flange carrying a flange extending upwardly from said door stop and inwardly, said closure flange lying forwardly of said front end of said header and terminating short of said wall.

8. In a railway house car having a side wall formed with a door opening, a header providing a trough secured to said wall, the front end of said trough being open, a front door stop secured to and along said wall adjacent to said door opening, said door stop terminating at said front end of said header, a door retainer secured to and along said car wall above said header, said retainer having a depending flange spaced outwardly of said header and lying above said door stop and a vertical closure member, said closure member having a flange extending upwardly from said door stop and inwardly and lying forwardly of said front end of said header, a flange extending forwardly from said door stop substantially parallel to said retainer flange, and a flange extending inwardly from said forwardly extending flange to said wall, said last mentioned and forwardly extending closure flanges extending downwardly a substantial distance below said header.
